BOTTLE FILLING AND CROWNING MACHINE

John Walter Flower, Wimborne, England

Application May 26, 1930, Serial No. 455,774, and
in Great Britain May 30, 1929

4 Claims. (Cl. 226—98)

This invention relates to rotary counter pressure bottle filling machines and the filling and crowning heads therefor.

The primary object of the invention is the provision in a machine of the above type of a liquid discharge outlet that directs the liquid in radial manner: Thus the liquid falls against and gravitates down the inner side of a bottle into which the outlet is introduced. By this means fobbing 10 of the liquid and consequent loss of gas, usually CO₂, contained in the liquid is reduced to a minimum. Further, the tube or conduit in which the discharge outlet is needs to extend into the bottle only a short distance and the stroke of 15 the bottle to and from the head before and after filling may be of correspondingly short length.

A crowning head or heads are incorporated with the filling head or heads so that the crowning operation can be performed easily and quickly 20 after the filling. The crowning heads may be in accordance with my co-pending application for Letters Patent Serial No. 456,641, filed May 28, 1930. This application includes mounting the crowning heads slidably on or with respect 25 to the filling heads so that the said crowning heads can be placed over and in alignment with filled bottles for crowning and thereafter retracted.

According to one method of carrying my invention into effect I provide a filling cock rotatably mounted in the filling and crowning head. Drilled in the filling and crowning head are two 30 passages connected respectively to the counter pressure gas and to the liquid supply, and a third passage for the return of counter pressure gas from the bottles, say to the top of the liquid supply chamber.

The body of the cock is so apertured and bored and communicates with the said passages 40 and with the bottle filling tube or conduit which extends downwardly from the filling and crowning head that, with a bottle positioned below the filling tube, a certain sequence of filling operations is effected upon rotation of the cock.

The filling cock is preferably provided with 45 an operating head or key having six equally spaced arms and the ports in the filling cock are advantageously so arranged that two bottles are filled per revolution of the filling cock.

The filling tube is provided with an inner or 50 gas tube, the annular space between these two tubes forming the liquid inlet and being in communication with the filling cock. The lower end of the gas tube is provided with the radial discharge outlet in the form of an outwardly pro-

jecting annular shoulder or equivalent with the filling tube (outer tube) terminating a little above this shoulder so that liquid passing down the annular space is deflected outwardly, i. e. radially, when it reaches the shoulder.

A cushion or packing surrounds the outer tube near the top thereof and prior to the filling operation the bottle is pressed up against this packing with the two concentric tubes extending down a short distance into the bottle neck.

The machine is suitable for filling beers, etc. into bottles, and may also be used for mineral waters with the addition of a suitable syruping device where necessary. The machine is however suitable for filling all kinds of liquids whether carbonated or "still" and the filling device may be used separately or in conjunction with other corking means.

A rotary filling and crowning machine with a counter pressure liquid feed in accordance with the invention is illustrated by way of example in the accompanying drawings in which:—

Fig. 1 is a front elevation of the machine with some of the parts omitted.

Fig. 2 is a part plan view of the machine 80 shown in Fig. 1.

Fig. 3 is a vertical section on an enlarged scale primarily of one of the filling and crowning heads.

Fig. 4 is a front view of the said head and

Fig. 5 is a plan view thereof.

Fig. 6 shows four sections of the plug in Fig. 3 taken on different planes.

Fig. 7 is a vertical section through part of the lower end of the machine, more particularly 90 through the oil container and a cylinder and its inlet and relief valves.

Fig. 8 is a vertical section of part of the liquid feed pan and

Fig. 9 is a detail in connection with an automatic declutching mechanism.

In the example according to the drawings the filling heads 1 are carried by arms 2 projecting radially from the underside of a feed pan 3 mounted on a flange 4 at the upper end of a sleeve 5. The sleeve extends downwardly into an oil container 6 at the lower part of the machine and its end is co-axially fixed to a worm wheel 7. The worm wheel carries a number of hydraulic cylinders such as 8 received by bores 9 spaced around it and each bore and hence each cylinder is aligned with one of the heads 1. A further support for the cylinders 8 is provided by a cover plate 10 fixed to a flange 5' on the sleeve 5. A worm 11 supported by the wall 6' of the con-

tainer 6 and driven from a suitable clutch rotates the wheel 7 and thus the cylinders, sleeve, and heads, etc. on top and bottom bearings 12 and 13 carried on a vertical shaft or column 14 fixed centrally of the bed plate 15.

The bottles to be filled and crowned are placed on a conveyor 16 whence they are transferred to stirrups 17 by a star wheel 18 driven by the stirrups engaging with rollers 19 on the underside of the said wheel. This manner of driving the wheel ensures that the bottles pass into the stirrups without fouling the sides thereof. In order to prevent bottles jamming between the points of the star wheel and a guide rail 20 a bell-crank lever 21 is pivoted on the conveyor table 22. The rollers 19 rock the lever as they pass its free end so as to turn the rubber-padded end of a lever 23 into the path of the bottles and check the leading bottles one by one until such time as they become correctly spaced with respect to the star wheel points. The levers 21 and 23 are movably connected together by a rod 24 and the parts are returned to the position shown by a suitably arranged spring.

As each stirrup passes the bottle-receiving position the rams 25 on the upper ends of which the stirrups are mounted are forced upwardly due to the hydraulic pressure produced in the cylinders 8 when pistons such as 26 on which rollers 27 are arranged are forced within the cylinder due to a rise in the cam track 28 as set out in my co-pending application Serial No. 456,232, filed May 27, 1930.

This upward movement introduces a liquid filling tube 29 and a gas tube 30 co-axial therewith in the head 1 into the neck of the bottle and presses the mouth of the bottle against an india-rubber sealing pad 31. The gas tube is surrounded by the filling tube in spaced relation so as to provide an annular passage 32 and the lower end of the tube 30 is shouldered at 33 whilst the end of the tube 29 is spaced from the shoulder and thereby provides an annular outlet with the shoulder 33 at the bottom thereof.

The head has a plug 34 on the stem of which is a six point star wheel 35 and as the head continues its travel the point in position 36 (Fig. 4) strikes a plunger 37' fixed on the machine and turns the plug through 60°. Upon the initial part of this turn the tube 30 and the passage 32 are connected with a snift hole 38 in the valve body and opening to atmosphere, by way of the lower parts of gas and liquid ducts 39 and 40 respectively in the valve body and a channel 41 in the surface of the plug 34, thus any liquid left in the tube 30 and the passage 32 from a previous filling runs into the bottle. The inner tube 30 is then opened to the gas under pressure in the pan 3 by way of a passage 42 in the plug, a passage 43 in the head and arm 2, and a tube 44 with its mouth in the gas at the top of the pan, whilst the annular space remains in communication with the hole 38 due to communication with 41. The gas under pressure thus fills the bottle and exhausts the stale air and gases that the bottle may contain through the hole 38 which may, if desired, be controlled by a needle valve (not shown) to prevent the too rapid exhausting of the bottle and wasteful outflow of the pressure gas. The final part of the first 60° turn completely isolates the bottle from atmosphere and keeps the said bottle in communication with the gas under pressure which continues to flow into it until such time as the pressures within the bottle and pan are balanced.

The succeeding arm 45 of the star 35 is thus brought into the position initially occupied by 36 and contacts with a plunger 37' which turns the plug a further 60°. The first part of this turn moves the passage 42 out of register with 39 and immediately thereafter a part-helical channel 46 in the surface of the plug connects the lower part of the duct 40 to the snift hole 38 and thereby slightly lowers the pressure of the gas in the bottle to subsequently ensure a complete emptying of a gas return passage 47, since any liquid left in this passage from a previous filling will interfere with or even prevent the filling of the succeeding bottles. Continued turning of the plug moves the channel 46 clear of 38 and 40 so as to seal the bottle from atmosphere, whilst a groove 48 in the periphery of the plug connects the lower part of 39 to the gas return tube 47 and due to the pressure in the bottle having been made lower than that in the pan a sharp down or back flow of the gas occurs and effectively empties the tube 47. Near the end of the said second 60° turn of the plug a diametral duct 49 connects the upper and lower parts of the duct 40 and a flow of liquid from a passage 50 in the arm 2 and valve body takes place and enters the bottle by way of the annular space 32 and the annular discharge outlet from which the liquid discharges radially due to the shoulder 33 and downwardly so as to 105 gravitate down the sides of the bottle and not fog, the displaced gas returning to the top of the pan by way of the tube 30 and a conduit provided by 39, 48 and 47 and a tube 47' which opens into the top of the pan.

The machine continues its travel whilst the bottle is filling and finally the star wheel point 51, now in the position initially occupied by 36 strikes a plunger 37' which turns the plug another 60° so that the gas and liquid supplies 115 to the bottle are discontinued and the plug is set for the next filling.

The channels and ports in the plug are provided, except 49, in duplicate, so that 180° turns of the plug complete the whole filling operations.

The cam track 28 then allows the ram and bottle to drop under the action of the spring 52 surrounding the ram when a crowning head 53 is slid over the bottle. Then the ram rises again and forces the top of the bottle into the 12: crowning head and after the crown is applied the said ram and bottle descend and the filled and crowned bottle is scooped off of the stirrup onto the table 22 by contact with a fence 54. The bottles pile one behind the other between 130 the fence and a guide rail 55 and reach the conveyor which takes them to the end of the table.

The upward thrust of the rams during filling and crowning is taken by a circular beam or track 56 carried by four posts on the bed plate 135 of the machine, the thrust being transmitted through tracking rollers 57, one on each head.

The crowning heads are slid to and from the crowning position by ramps 58 and 59 engaging rollers 60 on them which, together with the said 140 crowning head, are described in detail in my co-pending application Serial No. 456,641, filed May 28, 1930. The crowns are fed to the heads as they pass by mechanism according to my co-pending application Serial No. 457,347, filed May 29, 1930.

As set out in my co-pending application Serial No. 456,232, filed May 27, 1930, the pressure required on the ram during filling is less than that required for crowning and a relief valve 61 is 150

provided with the additional loading spring, cam track, etc., according to the said specification.

In the event of any of the stirrups not receiving a bottle the ram will make its full upward stroke towards the filling head and an ear 62 on the stirrup will lift a sleeve 63 and a semi-circular finger 64 fixed to the upper end of the sleeve. The finger extends round the leading side of its head and its free end 65 is brought, when the sleeve is lifted, into the path of the plungers 371, 2, 3, and wipes against them and presses them back against springs on their shanks so that the star 35 passes them without being operated. The sleeves 63 and the ears 62 are slideable on guide rods 66 extending between the cover plate 10 and the heads 1. These rods prevent the stirrups rotating about their axes.

In the event of a ram not descending completely it fouls the fence 54 and rocks it. The shaft on which the fence is rigidly mounted turns a finger 67 which acts through a connecting rod 68, an arm 69 fixed on a vertical shaft 70, the said shaft, and an arm 71 on the shaft and with a projection 71¹ on it, to rock a trip 72 and cause the end 73 of a bell crank weighted at 74 to drop and, by a connection from the end 75 of the bell crank, disengage the clutch, not shown, by which the worm 11 is driven.

If one of the bottles is broken during filling, say due to the counterpressure, a rush and loss into atmosphere of liquid and gas is prevented by check valves 76 and 77. The liquid and gas are fed to the pan through a gland 78. The inner tube 79 conveys the liquid into the pan and is controlled as to delivery by a float valve 80-81, whilst gas enters the top of the pan by way of a tube 82 surrounding 79. An adjustable snift valve 83 is provided in the pan.

The conveyor is driven by a suitable transmission from the shaft of wheel 11. This transmission includes a friction clutch adapted to slip if a piece of broken glass or the like wedges between the conveyor and the left hand end of the slot, in the table, in which the conveyor runs.

What I claim is:—

1. In a counter pressure bottle filling machine, a plurality of filling heads each with a counter pressure gas flow tube and a liquid passage adapted to discharge liquid radially into a bottle introduced to the head, cocks for controlling the flow of counter pressure gas and liquid, hydraulic rams for introducing the bottles to the heads and for removing them from the heads, cylinders for the rams, a worm wheel supporting and circumscribing the cylinders, a connection between the

worm wheel and heads, and means for rotating the worm wheel and hence the connection and the heads.

2. In a counter pressure bottle filling machine, a plurality of filling heads each with a counter pressure gas flow tube and a liquid tube defining with the gas tube a liquid passage adapted to discharge liquid into a bottle introduced to the heads, the discharge ends of the gas tube and liquid tube being relatively formed to compel a radial discharge of the liquid, cocks on the heads and star wheels on the cocks adapted to operate the cocks in steps for controlling the counter pressure gas flow and the liquid flow with respect to the bottles introduced to the head, means including hydraulic rams, and a cam track for controlling said rams for introducing the bottles to the head and for removing them therefrom, and means for rotating the heads and bottles.

3. A counter pressure bottle filling machine comprising a counter pressure feed pan, filling heads rigidly connected to the pan, each head having a counter pressure gas flow tube and a liquid passage adapted to discharge liquid radially into a bottle introduced to the head, and having a tracking roller, a track above the rollers, and cocks for controlling the flow of counter pressure gas and the flow of liquid between the pan and heads, hydraulic rams being aligned beneath the heads, cylinders for the rams, a worm wheel carrying and circumscribing the cylinders, a sleeve rigidly connecting the worm wheel and the pan, a vertical standard axially of the sleeve with top and bottom bearings on which the worm wheel and sleeve and the parts they carry rotate, and means for rotating the said worm wheel.

4. A counter pressure bottle filling machine comprising a counter pressure feed pan, filling heads rigidly connected to the pan, each head having a counter pressure gas flow tube and a liquid passage adapted to discharge liquid radially into a bottle introduced to the head, and having a tracking roller, a track above the rollers, and cocks for controlling the flow of counter pressure gas and the flow of liquid between the pan and heads, hydraulic rams being aligned beneath the heads, cylinders for the rams, a worm wheel in driving relation to the cylinders, a sleeve rigidly connecting the cylinders and worm wheel with the pan, a vertical standard disposed axially of the sleeve with top and bottom bearings on which the sleeve, worm wheel and cylinders rotate, and means for rotating the said worm wheel.
